(57) **CLAIM**

The ornamental design for a personal razor for shaving, as shown and described.

DESCRIPTION

FIG. 1 is a first perspective view of a personal razor for shaving in accordance with the present invention;

FIG. 2 is a second perspective view thereof;

FIG. 3 is a top view thereof;

FIG. 4 is a bottom view thereof;

FIG. 5 is a front view thereof;

FIG. 6 is a back view thereof;

FIG. 7 is a left view thereof; and,

FIG. 8 is a right view thereof.

The broken lines in the drawings depict portions of the personal razor for shaving that form no part of the claimed design.

1 Claim, 8 Drawing Sheets
